FORMERLY CASPAR HONEGGER, OF RÜTI, SWITZERLAND.

WEFT-SPINDLE TUBE FOR SPINNING AND WINDING MACHINES.

1,333,397.

Specification of Letters Patent. Patented Mar. 9, 1920.

Application filed October 22, 1918. Serial No. 259,218.

To all whom it may concern:

Be it known that I, EDUARD EGLI, a citizen of the Republic of Switzerland, residing at Rüti, in the Canton of Zurich, Republic of Switzerland, have invented certain new and useful Improvements in Weft-Spindle Tubes for Spinning and Winding Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In known processes the weft-threads for the weavers' shuttles of looms with automatic change of the weft-threads are spun, in the case of ring-spinning frames, on relatively stout wooden pirns (Northrop pirns) having a projecting ringed head; or, in the case of self-actors, on paper tubes, which can then be placed on spindles provided with a projecting ringed head. Further, the weft material intended for looms with automatic change of weft-thread is spun in ring-spinning frames on well known light weft-tubes, and these latter put on Northrop spindles as mentioned above, like the cops in the case of the self-actors, this being for the purpose, on the one hand, of increasing the working speed of the ring-spinning frame, and, on the other hand, for economy in transport. Weft threads are also wound off the paper tubes of the self-actors on to Northrop spindles.

The object of the present invention is a weft-spindle-tube for spinning and winding machines, the novel arrangement of which consists in the provision, on its lower end, of means for directly placing it in weavers' shuttles, for the automatic change of the weft-thread and projections and recesses enabling it to be firmly secured in the shuttle, in order that, in spinning in ring-spinning frames, it may be possible to dispense with the relatively heavy and expensive pirns with projecting ringed heads, with the putting of the known ringed throstle tubes on Northrop spindles, and, in the case of spinning with self-actors, with the employment of Northrop spindles and the re-winding on to Northrop pirns.

With the present weft-spindle-tube, a con-

siderable reduction in weight, and therewith a greater working speed and a smaller expenditure of power, are attainable, compared with spinning on Northrop pirns; and further, in comparison with weaving with Northrop pirns, or with cops put on Northrop spindles, less dead weight in the shuttle, and therefore less shock, a reduced wear of the "striking" parts, and less power for exchanging the thread-carrier.

By the omission of the expensive pirn and spindle material, a very considerable saving of material, and thereby of expense, is insured; there is less dead weight in transport and a great saving of labor effected, in comparison with the system in which the thread carrier is put on.

In the drawing, examples of the new weft-tube and its arrangement on a ring-spindle and on a self-actor spindle, as well as in a weaver's shuttle, are illustrated. Figs. 1 and 2 represent a novel thread-carrier placed on a ring-spindle and on a self-actor-spindle. Fig. 3 shows the novel weft-tube in the weaver's shuttle. Fig. 4 is a longitudinal section of the clamping spring. Figs. 5 and 6 represent weft-tubes improperly put on in effecting a change, and Figs. 7 and 8 illustrate other forms of the weft-tube.

The weft-tube 6, shown in Fig. 1 as placed on a ring-spindle 4 and in Fig. 2 on a self-actor spindle 5, has a part 8 which serves for fixing it firmly in the shuttle and for insuring the automatic change of the weft-tube. This part forms a backward extension of the part 10 of the slightly conical weft-tube which receives the weft-thread 9 and has two shoulders 11 which project slightly beyond the circumference of the tube. These shoulders may be formed in one piece with the weft-tube or may be applied thereto. The weft-tube may consist of wood, hard paper, paste-board, or the like.

In the shuttle 7 (Fig. 3), a fork-shaped clamping spring 12 is arranged, the "arms" of which have recesses 13 corresponding to the shoulders 11 of the weft tube. In these recesses, the shoulders 11 are inserted; the weft-tube being thereby securely held in the shuttle. In consequence of the exceptional lightness of the weft-tube, it is not necessary that the strength of the clamping spring 12 should be great; so that a light hammer and little power suffice for changing the

tube. The noise arising herefrom is only slight. If, in consequence of the shuttle not completely running into the shuttle-box situated on the weft-change side, the shoulders of the weft-tube, instead of coming into the recesses 13 of the clamping spring, only arrive adjacently thereto on the un-recessed parts of the spring (see Fig. 5), the first time that, following the change of the tube, 10 the shuttle runs to the left and strikes in the shuttle-box, the weft-tube 5 will, by reason of its *vis viva*, be driven axially so that the shoulders of the spindle 5 automatically come into the recesses 13 of the clamping 15 spring 12; the weft-tube thereupon assuming the correct holding position. Fig. 6 illustrates the case where, in consequence of the shuttle not having run sufficiently into the shuttle-box only one shoulder has been 20 pushed into the clamping spring. In this case, the weft-tube is held with sufficient firmness.

The weft-thread is spun or wound on the weft-tube, and this is put on a ring-spindle 25 4, (Fig. 1) or on a self-actor spindle 5 (Fig. 2), which combination is substantially lighter than cops on spindles with stout projecting ringed heads; and this very light tube can be put directly into the shuttle, 30 held firmly therein and readily changed.

In the form of construction shown in Fig. 7, the shoulders 11 for securing the weft-tube are formed by means of circumferential grooves 14.

Fig. 8 represents a weft-tube made of hard paper with sleeve 15 made of metal, for example, and shoulders 11 placed thereon.

As stated at the beginning, the present 40 weft-tube has great advantages by reason of the considerable saving in cost of production and transport, in power and labor,

and in the reduced wear of the parts employed in the changing.

What I claim is:—

1. A device of the class described, comprising, in combination, a shuttle provided with a clamping spring having a plurality of annular recesses forming flat depressions and flat elevations, a weft tube having at 50 its rear end a plurality of flat collars disposed so as to form between them recesses adapted to receive one of the elevations of the clamping spring, the surfaces between the elevations and depressions being perpendicular to the axis of the weft tube and the surfaces of the elevations and depressions being parallel to such axis.

2. A device of the class described comprising, in combination, a shuttle provided with a clamping spring having a plurality of annular recesses forming flat depressions and flat elevations, a weft tube, a metallic sleeve secured on the rear end of said weft tube and having a plurality of flat collars disposed so as to form between them recesses each adapted to receive one of the elevations of the clamping spring, the surfaces between the elevations and depressions being perpendicular to the axis of the weft tube and the 70 surfaces of the elevations and depressions being parallel to such axis.

3. A clamping spring for loom shuttles, comprising a pair of arms each having formed therein a plurality of recesses forming flat elevations and flat depressions, the surfaces of said elevations and depressions being parallel with the axis of the spring, and the surfaces between the elevations and depressions being perpendicular to such 80 axis.

In testimony whereof I have signed my name to this specification.

EDUARD EGLI.
